(57) CLAIM

The ornamental design for a flower top dessert, as shown and described.

DESCRIPTION

FIG. 1 is a perspective view of a flower top dessert.

FIG. 2 is a front plan view thereof;

FIG. 3 is a rear plan view thereof;

FIG. 4 is a right plan view thereof;

FIG. 5 is a left plan view thereof;

FIG. 6 is a bottom view thereof; and,

FIG. 7 is a top view thereof.

The broken lines in the drawings illustrate portions of the flower top dessert that form no part of the claimed design.
